UNITED STATES PATENT OFFICE.

CHARLES M. MANLY, OF BROOKLYN, NEW YORK.

INTERNAL-COMBUSTION ENGINE.

1,185,224.

Specification of Letters Patent. Patented May 30, 1916.

Application filed March 13, 1911. Serial No. 614,129.

To all whom it may concern:

Be it known that I, CHARLES M. MANLY, a citizen of the United States, residing at Brooklyn, county of Kings, and State of New York, have invented certain new and useful Improvements in Internal-Combustion Engines, of which the following is a specification.

My invention relates to internal combustion engines and more particularly to that type of engine wherein the fuel is injected into the cylinder in the liquid state.

The object of this invention is to provide means for vaporizing the fuel so introduced which is simple in construction and efficient in operation.

With this and other objects in view my invention comprises the novel construction and arrangement of parts hereinafter described and more particularly pointed out in the claims.

In the drawings—Figure 1 is a section of a portion of the cylinder of an engine of the type referred to provided with this invention; Fig. 2 is a perspective of one of the vaporizer plates; Fig. 3 is a side view partly in section of a modified form; and, Fig. 4 is a perspective of one of the plates thereof.

Referring to the drawings wherein like reference characters indicate like parts throughout the several figures, 1 indicates a portion of the top of the cylinder of an engine of the type referred to. Formed integral with the cylinder is a vaporizing chamber 2 having a top plate 3 bolted thereto. Depending from this plate is a bolt or rod 4 and attached to the rod is a plurality of spaced plates of a size to have a slight clearance between their perimeters and the wall 40 of the chamber. In Fig. 1 I have shown the plates to be seven in number and of these the bottom plate 5 is solid and at right angles to the rod 4 while the upper plates 6 are provided with a plurality of perforations 13 and are inclined relatively to each other and to the supporting rod 4, thereby forming diverging openings or spaces between the plates, extending from side to side of the chamber 2. A convenient means 50 of attaching the plates to the rod is shown in the drawing and comprises clamping nuts 7 on the rod above and below the plates, the upper plates being provided with central, integral hubs or bosses 8, the bores and 55 faces of the bosses being at the proper angle

to the faces of the plates to maintain the plates in the desired relative positions.

Set in the wall of the chamber 2 in such positions as to be opposite the widest spaces between the plates are several nozzles 9, to which are connected pipes 10 through which the liquid fuel is intermittently injected by a suitable pump mechanism, not shown. Also set in the side of the chamber 2 is the usual spark plug 11 for igniting the charge and mounted in the top plate 3 is a priming cup 12 of the usual construction.

The operation of the device will now be described. The engine is primed by introducing into the cylinder through the priming cup 12 a small quantity of a volatile hydrocarbon, as gasoline, before the liquid fuel, usually kerosene, is injected through the nozzles 9. The engine is then started in the usual manner. The heat developed by the explosion of the gasoline raises the temperature of the plates to a point sufficient to vaporize the kerosene injected through the nozzles 9 and thereafter the successive explosions maintain the temperature of the plates sufficiently high to vaporize each succeeding charge of fuel. I have found that the vaporization of the fuel is materially aided by the perforations in the plates and by arranging certain of the plates so that they present inclined surfaces opposite the bores of the nozzles 9. The perforations afford a larger radiating surface than can be obtained by solid plates in the limited space of the vaporizing chamber besides affording very hot passages through which the gasified vapor passes and insures that any fuel in the liquid state will be vaporized by dripping through them and the sharp edges of the perforations maintain a higher temperature than the body of the plates, and in addition, the sharp edges of the perforations serve to mechanically break up or atomize the liquid discharged against the plates through the nozzles. This latter result is better obtained by the inclined surfaces of the plates which presents the edges of the perforations in line of the injected fuel. This arrangement of the plates also prevents the fuel passing between the plates to the opposite side of the cylinder in a liquid state. The bottom plate is formed solid to catch and retain until it vaporizes, any liquid fuel that may drip through the upper plates.

In Figs. 3 and 4 I have shown a modified form of my improved vaporizer. In this form the perforated plates 6', instead of being of uniform thickness and inclined 5 relatively to each other, each have one face inclined relatively to the other face and to the bore for the rod. These plates are preferably arranged so that every other plate is reversed, that is, assuming one plate to 10 have its inclined surface the upper surface, the next plate is arranged with its inclined surface downward, and so on through the entire stack. The plates having their inclined surfaces adjacent are preferably ar- 15 ranged with their thick edges on the same side of the chamber thereby forming a diverging space into which the liquid fuel may be injected. The next pair of plates may have their thick edges adjacent a dif- 20 ferent portion of the chamber wall to uniformly distribute the metal throughout the chamber.

In Fig. 1 of the drawing I have shown the vaporizer as consisting of seven plates 25 and the chamber as provided with three nozzles for admitting the fuel while in Fig. 3 I have shown the vaporizer as consisting of eight plates and the chamber as having but one nozzle. It is to be understood, how- 30 ever, that with either form of vaporizer any desired number of plates and nozzles may be provided, since in large size engines where a considerable quantity of fuel is delivered at each charge it is desirable to have 35 several nozzles so that the fuel will be delivered in fine streams and more evenly distributed over the heated plates.

I claim—

1. In an explosive engine, the combina- 40 tion with a cylinder, of a plurality of plates mounted therein, certain of said plates being perforated and arranged in juxtaposition with their adjacent surfaces inclined with respect to each other, thereby forming a 45 plurality of V-shaped spaces between said

plates, and a plurality of nozzles arranged in said cylinder adjacent the widest por- tions of said V-shaped spaces.

2. A vaporizer for explosive engines comprising a rod depending from the head of 50 said engine, a plurality of plates carried by said rod, certain of said plates being perforated and having their surfaces inclined with respect to the adjacent surfaces of the adjoining plates, thereby forming 55 diverging spaces between the said plates, and means for injecting liquid fuel into said spaces.

3. In an explosive engine the combination with a cylinder of a rod depending from 60 the head of said cylinder, a plurality of plates supported on said rod, certain of said plates being perforated and having their surfaces inclined with respect to the adjacent surfaces of the adjoining plates, the 65 arrangement being such that the plates form a plurality of V-shaped spaces diverging toward different sides of said cylinder, and a plurality of nozzles arranged in said cylinder adjacent the widest portions of said 70 V-shaped spaces whereby liquid fuel may be injected between said plates.

4. In an explosive engine, the combina- 75 tion with a cylinder of a plurality of plates supported in said cylinder adjacent the top thereof and arranged one upon the other, said plates having their adjacent faces inclined oppositely to each other and provided with perforations to permit the passage of liquid and vapor from the top plate through 80 all the plates except the bottom plate.

In testimony whereof I have signed my name to this specification in the presence of two subscribing witnesses, this 11th day of March, 1911.

CHARLES M. MANLY.
